BEAD STRINGING MACHINE

Kenneth K. Roby, Minneapolis, and Paul A. Clark, St. Paul, Minn.; said Roby assignor to said Clark

Application June 30, 1933, Serial No. 678,530

16 Claims. (Cl. 173—244)

The present invention relates to a mechanism for automatically stacking perforated articles in such manner that the perforations therein are in alignment and is particularly directed towards a mechanism for stacking small insulating beads which are adapted to be strung upon electrical conductors whereby the conductors retain their flexibility but are well insulated from direct contact with adjacent exposed surfaces.

10 The beads for which the machine of the present invention has been particularly designed are of the type which are substantially cylindrical and having a hole running through the axis of the cylinder, one end of the bead being convex whereas the other end of the bead is correspondingly concave whereby the convex end of one bead is adapted to be received within the concave end of an adjacent bead with the holes through the beads in alignment.

20 One of the objects of the present invention is the provision of mechanism including a hopper adapted to contain a plurality of perforated articles, said hopper being provided with suitable openings whereby upon movement of the articles in respect to the opening the articles may pass, one at a time, through the opening and be received by a holder so that a series of the articles are stacked automatically in their proper cooperative relation.

30 Specifically, the means for moving the articles in respect to the opening in the hopper is an electrically driven paddle wheel which is placed in the hopper and is adapted to sweep the articles over the opening in the hopper.

35 The holder, in the particular embodiment of the invention to be hereinafter described, comprises a tubular member located below the opening in the hopper so that the articles, as they pass through the opening in the hopper, fall into the tubular member in the proper desired position.

40 A further object of the invention is the provision of a hopper having a plurality of openings therein for allowing the passage of articles therethrough, together with a plurality of holders, one for each opening, in combination with a single discharge means which cooperates with the plurality of holders in such a manner that any of the holders may be discharged of its articles at will. Specifically, the holders comprise a part 50 of a rotatable carriage which, upon rotation, successively brings the various holders into cooperative relationship with the discharge mechanism.

Other objects of the invention will become apparent as the description thereof proceeds.

45 For a more complete understanding of the in-

vention reference may be had to the following description and accompanying drawings, in which:

Fig. 1 is a side view of the mechanism comprising the instant invention. 5

Fig. 2 is an enlarged sectional view through the hopper, carriage, and discharge mechanism.

Fig. 3 is a sectional view through the hopper taken about on line 3—3 of Fig. 2, and

Fig. 4 is a sectional view taken through the carriage about on the line 4—4 of Fig. 2. 10

Referring to the drawings, a supporting base indicated at 10 supports a hopper generally indicated at 11, a carriage generally indicated at 12, a discharge mechanism generally indicated at 13, 15 and the other associated apparatus to be herein-after described.

Referring particularly to Figs. 2 and 3, the hopper comprises a cylindrical casting 14 having open ends, the upper end being closed off by a 20 removable cover 15 and the lower end being closed off by a rotatable hopper bottom plate 16. The hopper bottom plate 16 is provided with a plurality of spaced openings 17 which are substantially equally spaced about a circle whose center 25 coincides with the center of cylindrical casting 14. Each of the openings 17 has two substantially parallel sides 18, one of the ends 19 being curved whereas the other end is formed with an inwardly extending tongue 20. 30

The hopper bottom plate 16 rests upon and is secured to a horizontally disposed upper carriage plate 21 which is provided with a plurality of cylindrical vertical openings 22 one of which is disposed directly below each of the openings 35 17 in the hopper bottom plate 16. The lower portions of openings 22 are expanded and each of these expanded portions receives the upper end of a vertical tube 23. The lower ends of each of the tubes 23 are received by openings formed 40 in a lower carriage plate 24 which is pivotally mounted upon a carriage supporting plate 25. The tubes 23 have a relatively loose fit in the openings 22 in upper carriage plate 21 and the openings formed in the lower carriage plate 24 45 and these tubes completely pass through carriage plate 24 and rest upon carriage supporting plate 25. The carriage comprising the upper and lower carriage plates 21 and 24 and the tubes 23, together with the integral hopper bottom plate 16, 50 are rotatable as a unit about the center of the circle formed by the spaced openings 17 for a purpose which will be hereinafter described. Each of the tubes 23 is provided with one or more sight 55

openings 26. Upper and lower carriage plates 21 and 24 are secured together by rods 24A.

The hopper casing 14 is carried by supporting base 10 by means of a bracket 27 and the carriage supporting plate 25 is similarly secured to supporting base 10 by means of a bracket 28.

An electric motor 29 is provided with an extended shaft 30 which extends through the cover 15 of hopper 11 and also extends through the hopper bottom plate 16 and upper carriage plate 21. Mounted upon shaft 30 and within hopper 11 is a paddle wheel 31 which is provided with a plurality of paddles 32.

In operating the above described mechanism, the cover 15 of hopper 11 is removed and the hopper is supplied with a plurality of beads such as the one indicated at 33, it being noted that the bead 33 is substantially cylindrical and has a hole 34 running through its center, one of the bead ends being convex whereas the other is concave. The motor 29 is placed into operation and rotates paddle wheel 31 and paddles 32 in a counter-clockwise direction as viewed in Fig. 3 of the drawings. The paddles 32 move the beads around hopper bottom plate 16 and likewise moves them outwardly towards the periphery thereof. As the beads are swept across the opening 17, some of them will present their concave ends to the tongues 20 of the openings 17 whereupon such beads will fall through the openings 17 and enter the corresponding tubes 23, taking the position of the bead 33 shown in Fig. 2 wherein the concave end of the bead is turned upwardly. The next succeeding bead to pass through the corresponding openings 17 and enter the associated tube 23 will likewise enter the particular tube 23 with its concave end turned upwardly whereby its lower convex end will enter the concave end of the bead below it. In this manner, the beads are stacked in the tubes 23 with the convex end of each bead entering the concave end of the next adjacent bead and with the holes 34 through all of the beads in alignment.

The discharge mechanism 18 comprises a plate 35 which slides in a radial opening formed in carriage supporting plate 25. The end of discharge plate 35 is provided with a bent over end 36 which enters a hole 37 formed in carriage supporting plate 25 whereby the limits of movement of discharge plate 35 are predetermined.

When the carriage plate 35 is pulled out of its extreme position an elongated slot 38 therein is positioned directly underneath one of the tubes 23. Upon inward movement of discharge plate 35 a circular opening 39, which connects with elongated opening 38, is brought underneath one of the tubes 23. This circular opening 39 is large enough to allow the passage of the beads 33 therethrough.

After the apparatus has been in operation for a sufficient period of time, some of the tubes 23 will become filled with beads stacked in the manner hereinbefore set out as can be determined by viewing the tubes 23 through the sight openings 26. When it is desired to discharge one of the tubes 23, the carriage 12 is rotated until the lower end of the particular tube which it is desired to discharge is brought above the elongated slot 38 in carriage plate 35. The wire or rod upon which it is desired to string the beads contained in the particular tube 23, or a needle which may be thereafter used to string the desired conducting wire through the beads, is placed in slot 38 and moved up into the tube 23 through

the openings 34 in the beads stacked in such tube. The discharge plate 35 is thereupon moved inwardly so as to bring its circular opening 39 in registry with the bottom of the tube 23 whereupon the beads 33 contained therein may be lowered out of the tube and will be found to be threaded upon the rod or wire previously inserted. By repeating the above described operation, each and every one of the tubes 23 may be discharged whenever filled or at any other desired interval. The discharge plate 35 is provided with a portion 40 which is bent back upon itself and passes over the lower carriage plate 24. The end of this re-bent portion 40 is provided with a semi-circular opening 41 adapted to receive the tubes 23 whereby upon movement of the discharge plate 35 to discharge one of the tubes 23, that particular tube is received in the semi-circular opening 41 so that the tube 23 is properly positioned in relation to the circular opening 39 for discharge purposes and the complete carriage 12 is prevented from rotation during this discharge action.

In order to facilitate the entering of the beads 33 into the opening 17, it has been found desirable to agitate the beads 33 in addition to moving them by the paddles 32. In this particular embodiment of the invention, this agitation is accomplished by a motor 42 which is secured to the bent over end 43 of bracket 28. The shaft 43 of motor 42 supports an eccentric weight 44 with the result that upon rotation of shaft 43, the motor 42 and associated parts are caused to vibrate. This vibration is imparted to the beads 33 in the hopper 11 and is also imparted to the beads 33 contained in the tubes 23. The vibration thus imparted to these beads facilitates their moving around into such a position that their concave ends pass over the tongues 20 of the openings 17, pass through the openings 17, and into the tubes 23.

It should be noted that beads of this type must be stacked with a particular end of one bead adjacent a particular end of the next bead and this is accomplished by the provision of the tongues 20 whereby the beads 33 may only pass through the openings 17 in one direction and whereby those ends engaged by the tongues 20 are momentarily prevented from passing through the openings 17 with the result that the convex end first moves through the opening 17 and drops into the vertical tubes 23 whereby the beads always enter the tubes 23 with their concave ends turned upwardly.

The mechanism which has been hereinabove described when equipped with 24 hopper openings and 24 tubes has been found to stack insulating beads as small as $\frac{1}{8}$ inch in diameter and about $\frac{1}{4}$ inch in length at the rate of about 5,500 an hour and an operator is continuously kept busy in discharging the beads in the tubes 23.

From the foregoing description, it will be quite apparent that the present invention provides novel mechanism for stacking similar articles of any type and is particularly adapted to the stacking of perforated beads having an irregular configuration. While the specific embodiment of the invention has been herein disclosed, it is to be understood that many minor changes could be made therein and we intend to be limited only in the purview of the appended claims.

We claim:

1. A device of the class described for stringing elongated perforated articles, comprising, in com-

bination, a hopper adapted to receive a plurality of elongated articles having perforations extending therethrough in a direction parallel to the length thereof and which it is desired to stack with their perforations in alignment, said hopper being provided with an elongated opening in its bottom adapted to receive one of said articles and allow the same to fall from the hopper, means for tilting each article on end as it passes through said opening whereby it rests upon the next preceding article with their perforations aligned, and a holder for guiding said articles after they leave the hopper.

2. A device of the class described, comprising, in combination, a hopper adapted to receive a plurality of elongated articles having perforations extending through their length and which it is desired to stack with their perforations in alignment, the hopper being provided with an elongated opening in its bottom adapted to receive one of said articles and allow the same to fall from the hopper, means for tilting each of said articles upon end as it passes through said opening whereby the same falls upon the next preceding article with their perforations aligned, a holder for guiding said articles after they leave the hopper so as to maintain said alignment of their perforations, means for moving said articles in respect to the opening in said hopper to cause the same to pass therethrough, and means for agitating said hopper to assist said means for tilting each of said articles upon end as it passes through said opening.

3. A device of the class described for stacking insulating beads of substantially cylindrical shape and having a concave end, comprising, in combination, a hopper adapted to receive a plurality of such beads, said hopper having an opening therein conforming to the outline of said beads and including a tongue adapted to enter the concave end thereof whereby the beads may only pass through said opening in such manner that the concave end thereof passes through last, a holder for receiving the beads from the hopper and maintaining the same in alignment with all of their concave ends facing in the same direction, and means for causing said beads to pass through said opening.

4. A device of the class described for stacking objects having a concave end and a convex end, comprising, in combination, a guide plate having an opening therein conforming to the outline of said objects, said opening being formed to provide an extension adapted to enter the concave ends of said objects whereby the concave ends of said objects must pass over said extension in order to allow passage of the objects through said opening, the convex ends of said objects thereby first passing through said opening, means for moving said opening and objects in respect to each other to permit said objects to properly enter said opening, and a holder arranged to receive each of said objects as it passes through said opening and hold the same in the position it assumes in passing through said opening whereby said objects are stacked with all of their convex ends pointing in the same direction so that the convex end of each of said objects enters the concave end of the adjacent object.

5. A device of the class described for stacking cylindrical objects having a concave end and a convex end, comprising, in combination, a guide plate having an opening formed therein which conforms substantially to the shape of said objects and arranged to provide an extension

adapted to enter the concave ends of said objects whereby said objects can only pass through said opening if their concave ends pass over said extension resulting in passage of the convex ends thereof through said opening first, means for moving said objects and opening in respect to each other, and a holder for receiving said objects as they pass through said opening and for holding them in the position they assume in leaving said opening whereby the objects are stacked with all of their convex ends in the same direction.

6. A device of the class described, comprising, in combination, a tubular holder for receiving a plurality of perforated articles with their perforations in alignment, a discharge device normally preventing removal of said articles from said tubular holder and including a closure member for said tubular holder having an opening smaller than said articles and an intercommunicating opening sufficiently large to permit the passage of said articles therethrough, said smaller opening permitting the insertion of a threading member into the aligned openings of the articles in said tubular holder, and means for bringing said larger opening into registry with the stack of articles whereby they may be removed from said tubular holder in their threaded condition.

7. A device for positioning elongated articles end to end comprising, in combination, a hopper adapted to receive a plurality of articles, said hopper being provided with an elongated opening in its bottom adapted to receive said articles and allow them to fall therethrough, means adjacent said opening for retarding the falling movement of one end of said articles relatively to the other whereby they are turned up-end, and means beneath said openings for collecting said articles.

8. A device for positioning articles, each having a physical characteristic at variance with the general characteristic of the article, with said variant characteristics in alignment comprising, in combination, a hopper adapted to receive a plurality of articles, said hopper being provided with an opening in its bottom adapted to receive said articles and allow them to fall therethrough, means adjacent to said opening for engaging said articles as they pass through said opening and arranged to retard the portion of said articles having the variant characteristic relatively to the remainder of the articles, whereby those portions of the articles are caused to face uppermost, and means beneath said opening for collecting said articles.

9. A device for positioning perforated articles with their perforations in alignment comprising, in combination, a hopper adapted to receive a plurality of articles, said hopper being provided with an opening in its bottom portion adapted to receive said articles and allow them to fall therethrough, means adjacent said opening arranged to enter the walls of the perforations of said articles at one end and retard the falling movement of the contacted end relatively to that of the other end, whereby the articles are turned so that the perforations face vertically, and means below said opening for collecting said articles.

10. A device for positioning articles comprising a hopper having in its bottom portion a series of spaced openings, a series of collecting conduits beneath said hopper, the inlets to said conduits being in registration with the openings in the hopper, and means for rotating the bottom portion of said hopper and said collecting

conduit as a unit to cause the articles in said hopper to be agitated towards said openings and to pass therethrough into said collecting means.

11. A device for positioning articles comprising a hopper having in its bottom portion a series of spaced openings, a series of collecting conduits beneath said hopper, the inlets to said conduits being in registration with the openings in the hopper, means for rotating the bottom portion of said hopper and said collecting conduit as a unit, means abutting the outlet ends of said conduits for preventing said articles from passing therethrough, said means being movable relatively to the conduit structure and having therein a gate adapted to be brought into registration with said conduits selectively to permit discharge of articles from said conduits.

12. A device of the class described, comprising a hopper having in its bottom portion a series of spaced openings, a series of collecting conduits beneath said hopper, the inlets to said conduits being in registration with the openings in the hopper, means for rotating the bottom portion of said hopper and said collecting conduit as a unit, means rotatable with said conduits and abutting the outlet ends thereof for preventing said articles from passing therefrom, said means being movable with respect to the conduit structure and having therein a gate adapted to be brought into registration with said conduits selectively to permit discharge of articles from said conduits.

13. A device for positioning elongated articles comprising a hopper having a rotatable bottom portion, an elongated opening in said bottom portion spaced from the axis of rotation and having its minor axis disposed substantially in a radial plane, said opening being adapted to receive said articles and allow them to fall therethrough, means adjacent said opening for retarding the falling movement of one end of said articles rela-

tively to the other, and means beneath said opening for collecting said articles.

14. A device for positioning elongated articles comprising a hopper having a rotatable bottom portion, an elongated opening in said bottom portion spaced from the axis of rotation and having its minor axis disposed substantially in a radial plane, said opening being adapted to receive said articles and allow them to fall therethrough, and means beneath said opening for collecting said articles.

15. In a bead stringing device, the combination of a hopper adapted to contain a plurality of perforated articles, a stacking structure having a plurality of vertical stacking channels, means for delivering the perforated articles from said hopper into said stacking channels with their perforations in alignment, means for retaining the thereby aligned perforated articles in said stacking channels, and discharge means co-operating with the retaining means arranged for selective discharge of said articles from said channels, said discharge means being relatively shiftable and including means for permitting the insertion of a member to be strung through the aligned perforations of said articles while they are held in said stacking channels.

16. In a bead stringing device, the combination of a hopper adapted to contain a plurality of perforated articles, a stacking structure having a vertical stacking channel, means for delivering the perforated articles from said hopper into said stacking channel with their perforations in alignment, means for retaining the perforated articles in said stacking channel while permitting a member to be strung to be inserted through the aligned perforations of said articles, and means for releasing said articles from said channel.

KENNETH K. ROBY. 40
PAUL A. CLARK.
